UNITED STATES PATENT OFFICE.

CLEVELAND F. WITHERBY, OF BOSTON, MASSACHUSETTS; LUCIA W. GREELEY
ADMINISTRATRIX OF SAID WITHERBY, DECEASED.

ARTICLE FORMED OF NARROW WEBBING.

Application filed April 13, 1923. Serial No. 631,784.

This invention relates to the finishing of narrow strips of textile material such as the webbing commonly used in garment supporters and the object is to provide an improved construction whereby such strips can be given an attractive and durable finish and one which will if necessary serve as a reinforcement. As an example of my invention I have here shown an illustrative form there-
of applied to the buttonhole loops of a suspender end and this application of the invention will be readily understood by reference to the following description taken in connection with the accompanying drawings.
15 wherein:

Fig. 1 is a front elevation of a suspender end;

Fig. 2 is a view of web from which the buttonhole loop is formed; and

20 Fig. 3 is a section on an enlarged scale on the line 3—3 of Fig. 1.

For the purposes of illustration I have herein shown the invention as applied to a suspender end such as is disclosed in the application of Alfred M. Ziegler, Serial No. 522,258, filed Dec. 14, 1921, and embodying a pair of buttonhole loops 5, each comprising a short piece or strip of textile webbing having the ends folded around an elastic 25 cord 7, embodying a rubber spring with a braided cover, and secured thereto by stitching 9. My invention more particularly relates to providing a finish for the free ends of these pieces of webbing which in the present instance serves as a reinforcement preventing the tearing out of the buttonholes 30 under strain.

Referring to Fig. 2, I have there shown the section of webbing 5 before the end thereof is finished. As there indicated I may fold back the extreme edge 13 thereof to provide a doubled end as shown in Fig. 1 immediately under the buttonhole and preferably also the sides of the web are pleated 35 inwardly at the sides along the dotted lines of Fig. 2 forming the triangular pleats 15 and thus giving a pointed shape or finish to the end of the web. This method of folding is not in itself novel.

40 To secure the folded parts of the web in position they are sewed together and this sewing preferably extends throughout a substantial area of the folded portions. To effect this I prefer to utilize stitches or rows 45 of stitches extending substantially length-

wise of the web and substantially parallel to each other and the length of these stitchings may be progressively varied so that the stitching forms as a whole a triangular block of stitching corresponding in contour 60 substantially to the contour of the end of the buttonhole loop beneath the buttonhole, although conveniently smaller in area, and securely darning together the folded portions. The stitching 17 is conveniently effected by machine and in this case utilizes a bobbin or thread at the back, but I have not thought it practicable to illustrate in Fig. 3 the use of two threads but have merely indicated the stitches 17 in a more or less 65 diagrammatic fashion. The variation in the length of the stitches may be effected automatically by the use of a suitable cam on the sewing machine and it will be noted that they are all applied substantially parallel, 70 extending in the same direction, and there is no need for the operator to turn the work during the operation. Thus the construction, while being a very strong one, is very rapidly and simply made.

75 A series of stitchings 17 on the face of the webbing emphasizes the contour of the end portion thereof and if closely set together have the appearance of embroidery and may be of a color contrasting with that 80 of the web. A particularly ornamental effect is obtained in the case of a suspender end of the type herein described wherein the bar of stitching 9 and the stitching 17 are 85 made of the same attractive color.

90 I have described in detail one particular embodiment of my invention as applied to the construction of a suspender end. Obviously it is adaptable to the finish of the ends of narrow members utilized in other 95 garment supporters or in other relations whether or not subserving the additional function of providing a buttonhole reinforcement as in the present instance. What I claim as new and desire to secure by Letters Patent I shall express in the following 100 claims.

Claims:

1. In an article of the class described, a strip having a buttonhole therein and portions folded inwardly and substantially to the longitudinal median line of the strip providing an end of multiple thickness, the thicknesses of the end being secured together solely by a block of stitches beyond 105 110

and in alignment with the buttonhole securing the several plies together thereby to utilize the inwardly folded portions as a reinforcement.

5. In an article of the class described, a strip having a buttonhole therein, an end of multiple thickness beyond the buttonhole presenting portions inwardly folded substantially to the longitudinal median line of the strip and providing additional plies

and a block of parallel longitudinal stitches beyond and in alignment with the buttonhole extending through the end and the extra plies thereof and securing them together whereby to utilize said additional 15 plies as a reinforcement.

In testimony whereof, I have signed my name to this specification.

CLEVELAND F. WITHERBY.
